BY D. Shepherd
ATTORNEY

UNITED STATES PATENT OFFICE.

EDWARD F. LOEFFLER, OF COLUMBUS, OHIO.

ARTIFICIAL LIMB.

SPECIFICATION forming part of Letters Patent No. 703,431, dated July 1, 1902.

Application filed March 24, 1902. Serial No. 99,566. (No model.)

To all whom it may concern:

Be it known that I, EDWARD F. LOEFFLER, a citizen of the United States, residing at Columbus, in the county of Franklin and State of Ohio, have invented a certain new and useful Improvement in Artificial Limbs, of which the following is a specification.

My invention relates to the improvement of artificial limbs, and has particular relation to the improvement of the ankle-joint therefor or jointed connection between the foot and leg.

The objects of my invention are to provide a simple and effective ankle-joint of improved construction and arrangement of parts whereby a natural movement of the foot may be attained, to so construct my improved ankle-joint as to insure the same notwithstanding great strain and wear and obviate the necessity of employing the usual heel cord or cords, and to produce other improvements the details of construction of which will be more fully pointed out hereinafter. These objects I accomplish in the manner illustrated in the accompanying drawings, in which—

Figure 1 is a central longitudinal section through the heel portion of the foot and the lower portion of the leg. Fig. 2 is a sectional view on line $x-x$ of Fig. 1. Fig. 3 is a detail view in perspective of the lower end of the leg-section. Fig. 4 is a detail view in perspective, showing the upper side of the leg-plate. Fig. 5 is a sectional view through a portion of the foot, taken on line $y-y$ of Fig. 2, the leg being omitted from the view; and Fig. 6 is a view in perspective showing the upper side of the foot or ankle-plate.

Similar numerals refer to similar parts throughout the several views.

1 represents an artificial foot-body the upper side and rear portion of which is provided with an elongated recess 2, and on the upper surface of this recessed portion is secured a bearing-plate 3, of metal or other suitable material, this bearing-plate being, as indicated in the drawings, formed with a transverse groove or rounded depression 4, said grooved portion having formed therein transversely on opposite sides of the center of the length of the groove V-shaped depressions 5. Through the front or toe portion of the plate

3 is formed a mortise or elongated opening 6, which, as indicated in the drawings, is continued downward through the foot-body 1 into a comparatively large under side socket 7. At the center of the length of the grooved portion 4 of the plate 3 is also provided an opening 8, which is likewise continued downward through the instep portion of the foot-body, as indicated at 8^a . 9 represents the base portion of the leg, said leg being hollowed in the usual manner to a point within said base. Secured by means of bolts 10 to the under side of the leg-base 9 is a bearing-plate 11, this plate being, as indicated more clearly in Fig. 3 of the drawings, formed with a central transverse rounded projection 12, the central portion of said projection being slotted, as indicated at 13, and the surface of the projection 12 being formed on opposite sides of said slot with V-shaped projections 14, corresponding with the recesses or depressions 5 of the foot-plate 3, which are adapted to receive the same. In its forward portion the plate 11 is formed with an elongated opening 15, through which projects into a socket 16 of the foot the upper end of a bolt or rod 17, the latter having extending through its upper end portion a pin 18, the projecting end portions of which are adapted to bear in an upper side grooved seat 19 of the plate 11. The lower and downwardly-extending end portion of the bolt 17 is threaded and adapted, as indicated in Fig. 1 of the drawings, to pass through the slotted opening 6 of the foot-plate 3, thence downward into the socket 7 of the foot. Within the socket 7 the bolt 17 is surrounded by a tubular body 20, preferably of rubber, and beneath this tubular body the threaded end of the bolt is adapted to receive a nut 21. Bearing loosely in the rounded transverse depression 12 of the plate 11 is the horizontal head 22 of a T-bolt 23, the downwardly-extending stem portion of which passes loosely through the slotted opening 13 of said plate. This stem portion likewise passes through the opening 8 of the plate 3 and, as indicated in Fig. 1, extends down through the foot-opening 8^a , being provided on its lower threaded end with a nut 24.

In order to impart desirable strength to the leg-plate 11, I preferably form the same, as

indicated in Fig. 4, with upwardly-projecting parallel strengthening-ribs 25, these ribs being adapted to extend into the wood base of the leg.

5 In order to prevent direct contact of the upper and lower metal plates 11 and 3, I provide between said plates a strip or layer 26 of buckskin or other suitable yielding material, and between the forward portions of said

10 plates I may also insert a strip 27 of rubber.

From the construction shown and described it will be seen that by the employment of the T-bolt 23 a central hinge connection is produced between the leg and foot and that a 15 further hinge connection is produced between the forward portion of the leg-base and the foot-body by the employment of the hinge-bolt 17. These ankle-joint connections will permit, as will readily be understood, of the natural rocking action of the leg on the foot, the forward connecting or hinge bolt 17 operating to draw or return the leg to its forward position without the necessity of employing the usual heel-cords. It will also be 20 seen that by the employment of the intermediate yielding bearing 26 between the upper and lower plates said plates are retained out of contact without interfering with the rocking action of the leg upon the foot, inasmuch 25 as the yielding nature of said bearing-strip permits of its being compressed between the

bearing parts of the plates and taking the form thereof.

It will be observed that my improved ankle-joint is so constructed as to withstand great 35 strain and that the parts thereof may be strong and durable.

Having now fully described my invention, what I claim, and desire to secure by Letters Patent, is—

40 In an artificial limb, the combination with an artificial foot-body, and a fixed plate on its upper side having a transverse rounded recess, of a foot-body having a fixed under side plate 11 provided with a rounded depressed portion 12, a T-bolt having its head portion loosely mounted in the plate depression 12 and having its stem portion passing loosely through opposite openings in said plates 11 and 3 and through the foot-body, and a hinge-bolt 17 independent of the bolt 23 having its upper end hinged in connection with the foot-body at a point in the forward portion thereof, said bolt extending downward loosely through openings in said plates and within a 45 50 55 socket of the foot and being provided within said socket with a yielding bushing, substantially as specified.

EDWARD F. LOEFFLER.

In presence of—

C. C. SHEPHERD,

P. S. KARSHNER.
